UNITED STATES PATENT OFFICE.

FREDERICK C. DOLCATER, OF ROCHESTER, NEW YORK, ASSIGNOR TO MONTAGUE
MAILING MACHINERY CO., OF CHATTANOOGA, TENNESSEE, A CORPORATION
OF TENNESSEE.

SELECTIVE PRINTING-PLATE.

1,259,001.

Specification of Letters Patent. Patented Mar. 12, 1918.

Original application filed August 5, 1914, Serial No. 855,238. Divided and this application filed January 30, 1917. Serial No. 145,480.

To all whom it may concern:

Be it known that I, FREDERICK C. DOLCATER, a citizen of the United States, and resident of Rochester, New York, have invented certain new and useful Improvements 5 in Selective Printing-Plates, of which the following is a specification.

My invention relates to selective printing plates which are intended to be fed through 10 a printing machine for making impressions therefrom, the plates being selected for making these impressions as may be predetermined upon, or the selective means being adapted to coöperate with actuating mechanism 15 for adding means so that the values represented by the plates may be transferred to the adding mechanism, or the selective feature of the plate may be employed for other purposes.

20 The invention is shown in the accompanying drawings, in which—

Figure 1 is a plan view of a printing plate having the selecting means thereon.

Fig. 2 is a sectional view of the plate.

25 Fig. 3 is a plan view of a printing plate having selecting embossings for controlling or determining the transfer of the value represented by the plate to adding mechanism.

Fig. 4 is a view of the opposite face of the 30 plate from that shown in Fig. 3.

Fig. 5 is a view of certain elements of an apparatus intended to coöperate with the printing plate of Figs. 1 and 2.

While the printing plate may be employed 35 in different ways, I illustrate, as an example, in Fig. 5, certain of the elements of an apparatus which are intended to coöperate with the printing plate in performing its functions. In this view 28 represents a table 40 having a runway to receive the depressed margin of the printing plate at 14 and also a second runway to receive the other depressed margin of the plate, as at 21, this second runway having suitable means, as a 45 reciprocatory bar indicated at 20, for giving the printing plates a step by step movement along the runway to feed them to the impression point under an impression head (not shown).

50 The printing plates are preferably of the

well known Montague type manufactured under patents of Owens No. 939,739, November 9th, 1909, and Lee No. 982,076, January 17th, 1911. These plates are provided with embossed printing characters from which 55 the impressions are made, and in my present invention I employ selective means to determine whether or not the plates are to be printed from, these selecting means being indicated in Figs. 1 and 5 at X. Coöoperating 60 with these selecting points, or projections, I show, in Fig. 5, contact points, or a single contact point may be used, this point, or points, being indicated at Y and being carried removably and interchangeably in a 65 holder 26. This holder may be constructed in various ways, but I prefer to form it of insulating fiber having slots or openings for receiving the detector points or fingers Y. These detector fingers are rubber covered at 70 their exposed portions, excepting their extreme ends, which are left bare to contact with the selecting points or embossings on the printing plates. The holder 26 is carried on stems, one of which is shown at 27, movable vertically and operated by a lever 32 pivoted at 31. When the contact head is brought down it will cause its fingers Y to contact with the selector embossings X and this, through certain electrical connections, 75 can be made to control the operation of the impression head at the proper time for thus determining whether or not an impression shall be made from this particular plate. As the mechanism coöoperating with the plate 80 forms no part of the present invention, I do not think it necessary to further describe such mechanism.

It will be observed that the record plates having the selective device embossed thereon 90 are of advantage over any form of plate having removable tabs or other adjustable selective means. The plate can be made of a selective character at the same time that the address or information is embossed thereon, that is, while the plate is in the machine being embossed with the address it can be embossed at the same time and by the same machine with the character or characters 95 which are to classify the plate.

Furthermore, it sometimes happens that a customer must be transferred from one class to another. To do this, it is simply necessary with my invention to blank out, *i. e.*, press 5 down or obliterate the selector character and reëmboss the plate with the selector character at the proper point to put the customer in his proper class. With the embossed selector devices danger of loss of identity of the plate is prevented.

By employing alphabetical characters or numbers as the selective devices, the class or classes to which the plate belongs can be read at a glance. For instance, if the 15 letter A appears as the selective character, the plate belongs to the A or first class. If C appears it can be seen that it belongs in the third or C class. Each class, therefore, will be designated by its own particular sign or combination of signs which will be different from the signs or combination of signs designating other classes. These signs will not only be distinctive in themselves, but their location will be distinctive; 20 thus A will occupy the first position; D the fourth, and so on throughout the list of signs, so that the operator, in embossing the plate, will be able to place the sign in proper position quickly and certainly, and the liability of mistake will be reduced.

Furthermore, the embossed classifying sign can be printed on the wrapper, envelop, card or other matter, because the said sign is raised from the main body of the plate 35 just as the letters or characters of the address or other information is raised or embossed. By reason of this the article when printed will have a class indication thereon by which it may be identified and treated 40 differently and separately as may be desired from all printed articles belonging to other classes.

The plate has a main portion with embossed characters thereon, and it has margins offset to one side of the plane of the 45 plate by which the plate is guided. The main portion of the plate is elevated and the printing characters are thus brought to the proper plane.

50 The selecting embossings are made in this raised or main part of the plate. These embossings are made preferably near one edge of the plate, and it will be noticed that the detector plate is so located that its fingers 55 will extend over the guideway in the table and over the depressed rolled margin of the plate into position to contact with the selective embossings on the plate. The plate feeder is arranged below the surface of the 60 table and in position to engage one of the depressed margins of the plate.

Instead of employing selector embossings for controlling impressions, I may utilize such embossings for controlling other char-

acters of work, such as the transfer of values 65 which the printing plates represent to adding mechanism.

In certain classes of work, for instance where a number of checks are being printed, it is desirable to register the values that 70 the plates represent on accumulator mechanism, so that when the list of plates has been run through the machine, the total will appear, and an imprint of this total may be made either on a separate slip or 75 on the record strip or sheet which has just received thereon the list of items.

Referring to Figs. 3 and 4, the printing plates are adapted to receive embossings X' at or near one end thereof, representing 80 numbers of the desired denominations.

The spaces for receiving the embossings are indicated by the lines X² in Fig. 3, and these lines may be impressed in the back of the plate when it is formed. I show as 85 an example five columns representing units, tens, hundreds, etc., and each column having nine spaces representing digits running from 1 to 9. I have indicated the position of these digits by the numbers 1 to 90 9. Supposing the plate is to represent a value of one hundred and eighty-six dollars and twenty-five cents, the embossings would appear in the positions indicated in Figs. 3 and 4, and when the printing plate 95 reaches a certain position in the machine, certain mechanism would contact with these embossings and thus determine the proper operation of adding mechanism to take off the value from the plate which it 100 represents, this plate, of course, having embossed printing characters in addition to the selector embossings.

I do not think it necessary to show herein the character of the adding mechanism to 105 be controlled by the selector embossings on the plate.

This specification is a division of that filed by me August 5th, 1914, Serial No. 855,238.

110

I claim as my invention:—

1. A record plate having printing characters embossed thereon, and a selecting embossing consisting of an alphabetical sign or figure embossed in the plate, and adapted to be printed substantially as described.

2. A record plate having printing characters embossed thereon belonging to a prescribed series and having a selecting character or characters also embossed in the plate corresponding to one of the prescribed series of characters to which the said embossed printing characters belong, said selecting characters occupying a position on the said plate corresponding to its position in the series of characters to which it belongs, substantially as described.

3. A record plate having printing characters embossed thereon, and an embossed selecting character substantially as high as the printing embossings, and adapted to be printed, substantially as described.

4. A record plate having a main portion with margins rolled and in a plane to one side of the main plane of the plate, the

main portion of the plate having printing characters embossed therein, and having a 10 selecting character also embossed in said main portion and wholly within the margin of the plate, substantially as described.

In testimony whereof I affix my signature,

FREDERICK C. DOLCATER.
